UNITED STATES PATENT OFFICE.

HENRY CSANYI, OF NEW YORK, N. Y., ASSIGNOR TO MAXIVOLT PRIMARY BATTERY CO., OF NEW YORK, N. Y., A CORPORATION OF NEW JERSEY.

INCANDESCENT ELECTRIC LAMP.

1,124,213.

Specification of Letters Patent.

Patented Jan. 5, 1915.

Application filed November 3, 1913. Serial No. 798,929.

To all whom it may concern:

Be it known that I, HENRY CSANYI, a subject of the King of Hungary, residing at New York, in the county of New York and 5 State of New York, have invented new and useful Improvements in Incandescent Electric Lamps, of which the following is a specification.

This invention relates to incandescent 10 electric lamps, and it may be employed with lamps used by miners and other persons whose duty calls them into rooms, mines, and other places in which the atmosphere may be very highly charged with some explosive such as gas, fine coal dust, or other 15 substance that is liable to explode when exposed to a flame, a spark or a glowing filament.

One of the objects of this invention is to 20 provide an electric lamp, preferably of portable type, with a safety device in which the lamp bulb is supported in a telescopic socket slidable in the lamp casing or reflector, said socket being held by the front lens or window 25 dow of the casing in position to close the circuit through the lamp filament and maintain it closed, but on the breakage of said lens or window the socket will under the tension of a suitably disposed spring open 30 the circuit and immediately extinguish the lamp.

To set forth more clearly the novel features of the present invention attention is directed to the accompanying drawings 35 illustrating the preferred form of the invention in which—

Figure 1 is a vertical central sectional view through a reflector provided with the improved safety device. Fig. 2 is a front 40 elevation of the same. Fig. 3 is a perspective view of an incandescent electric lamp and its socket removed from the casing.

In the drawings 10 indicates an incandescent electric lamp carried within a casing 45 which in the present instance is in the form of a conical reflector 11 closed at its larger end by a circular window in the form of a lens 12 held in position by a spring ring 13 fitted between the outer periphery of the 50 lens, and the exterior edge of a bead 14 formed on the reflector. At the apex of the reflector opposite the window 12, or wherever is most convenient is formed a tubular stem 15 filled at its outer end with an insulating disk 16 through which passes a pin

17 forming one terminal of an electric line, the other terminal being formed by the tubular stem 15 to which the other line wire is directly connected. Fastened on the pin 17 within the tubular stem is a helical 60 spring 18 that may be compressed, and which forms in connection with the pin 17 a part of the circuit.

The electric lamp 10 screws into the threaded extension 19 of a sleeve 20 slidably 65 mounted in the inner end of a tubular stem 15 and coöperating therewith to form the lamp socket; the sleeve 20 is provided with a lateral flange 21 from which project a plurality of divergent fingers 22 that extend 70 toward and bear upon the window or lens 12 when the lamp is in operative position. The extension 19 and the fingers 22 project in the same general direction, that is in a direction opposite to the direction in which 75 the sleeve 20 projects. The fingers 22 are of such length as to project beyond the reflector when the lens or window 12 is removed, and are held in such position by the spring 18 which presses the lamp socket forward 80 within the reflector in order to open the circuit through the contacts, but when the lens is placed in position and pressed to its seat it bears upon the fingers 22 forcing the socket backwardly in the stem 15 to close 85 the circuit through the contacts. The lens or window 12 is held in position by the spring ring 13, as previously stated.

As constructed the lamp will burn when the circuit is closed through the line wire 90 continuously so long as the window or lens remains intact or unbroken, but should the latter be fractured pressure is removed from the fingers 22 and the spring 18, permitting the latter to expand and push the lamp 95 socket forward, thereby opening the circuit and extinguishing the light.

What I claim is:—

1. An electric lamp comprising in combination, a socket having two insulated conducting parts, a movable conducting part in contact with one of said first named conducting parts and through which the current for the lamp passes, displacing means tending to displace said movable part to 100 put the lamp out of circuit, a frangible part, and a member in contact with said frangible part and holding said displacing means in a position to maintain the circuit through 105 the lamp. 110

2. An electric lamp comprising in combination, a socket having two insulated conducting parts, a movable conducting part in contact with one of said first named conducting parts and through which the current for the lamp passes, displacing means tending to displace said movable part to open the circuit and extinguish the lamp, a frangible part, and a member in contact with said frangible part and holding said displacing means in a position to maintain the circuit through the lamp.
3. A casing for an electric lamp having a frangible window, and a lamp socket sleeve mounted to slide on said casing and a member between said window and said sleeve for holding said sleeve in circuit with line terminals on said casing until said window is broken.
4. A casing for an electric lamp having a frangible window, a lamp socket sleeve mounted to slide in said casing, and a member on said socket sleeve pressing against said window to hold said sleeve in circuit with line terminals on said casing until said window is broken.
5. A casing for an electric lamp having a frangible window, a lamp socket mounted to slide in said casing, a member on said socket pressing against said window to hold said socket in circuit with line terminals on said casing, and means to move said socket forward and open the circuit upon fracture of the window.
6. A casing for an electric lamp having a frangible window, a lamp socket mounted to slide in said casing, fingers on said socket pressing against said window to hold said socket in circuit with line terminals on said casing, and a spring to move said socket forward and open the circuit upon fracture of the window.
7. A casing for an electric lamp having a frangible window on one side and a tubular stem fitted with line terminals, a lamp socket slidable in said stem from which project fingers bearing on said window and holding said socket in electric circuit with said terminals, and means in said tubular
- stem for projecting said socket forward 50 when the window is broken to open said circuit.
8. A casing for an electric lamp having a frangible window on one side and a tubular stem fitted with line terminals, a lamp 55 socket slidable in said stem from which project fingers bearing on said window and holding said socket depressed within said stem in electric circuit with said terminals, and a spring in said stem bearing on said 60 lamp socket to project it forward and open said circuit when said window is broken.
9. A socket member for an incandescent lamp consisting of a sleeve extending in one direction, and having an extension projecting in the other direction to receive the lamp bulb, and having means projecting from said sleeve in the same direction as said extension for engaging a part of a lamp casing to retain the socket member in a lamp 70 socket.
10. A socket member for an incandescent lamp consisting of a sleeve extending in one direction, and having an extension projecting in the other direction to receive the 75 lamp bulb, and having a plurality of fingers projecting from said sleeve in the same general direction as said extension for engaging a part of a lamp casing to retain the socket member in a lamp socket.
11. A socket member for an incandescent lamp, consisting of a sleeve extending in one direction and having an extension projecting in the other direction to receive the lamp bulb, a lamp bulb attached in said 85 extension, said member having a plurality of fingers projecting from said sleeve in the same general direction as said extension for engaging a part of a lamp casing to retain the socket member in a lamp socket, said 90 fingers projecting beyond said bulb.
- In testimony whereof I have hereunto set my hand in presence of two subscribing witnesses.

HENRY CSANYI.
